UNITED STATES PATENT OFFICE.

JAMES R. FLEMING, OF SCRANTON, PENNSYLVANIA.

JOURNAL BOX.

Application filed May 17, 1919. Serial No. 297,727.

To all whom it may concern:

Be it known that I, JAMES R. FLEMING, a citizen of the United States, and a resident of Scranton, in the county of Lackawanna and State of Pennsylvania, have invented certain new and useful Improvements in a Journal Box, of which the following is a full, clear, and exact description.

Among the principal objects which the present invention has in view are: To amplify the lubricant of journals operated in conjunction with boxes of the character mentioned; to provide reservoirs for lubricant within the body of the journal-bearing forming members; to conserve lubricant; and to provide means for automatically lubricating said journals.

Drawings.

Figure 1 is a top plan view of a fragment of a bolster plate for use in conjunction with boxes constructed and arranged in accordance with the present invention.

Figure 2 is a vertical cross section, section being taken as on the line 2—2 in Figure 1.

Figure 3 is a top plan view of a self-centering chair forming a detail of the herein disclosed box.

Figure 4 is a longitudinal section of said chair, the section being taken as on the line 4—4 in Figure 3.

Figure 5 is a bottom plan view of said chair.

Description.

The journal box herein disclosed is particularly designed for employment on cars used in coal mines and similar installations. The road beds in such installations are usually constructed rapidly and somewhat crudely, as the roads are expected to be more or less temporary. The cars for such use are rarely provided with springs for supporting the load. As a result of the inequality of the tracks and of the absence of springs which would maintain the wheels in engagement with the track, provision is made to permit the axle to drop in these boxes, otherwise any one of the wheels might be held by the box where the rail on one side of the track is depressed, and thereby, run the risk of the flange of the wheel becoming disengaged from the side of the rail. Should such a condition arise on a curve, the opportunity for disaster is evident, particularly, if the drop in the track

should happen to be on the outer side of the curve. In such cases, the car would become derailed.

In the present construction this need is accommodated by increasing the journal opening 10 and by lowering the upper edge of the flanges 11, which are provided at the opposite ends of the pocket formed by the under body 12 of the journal casting 13.

The reservoir formed by the flanges 11 and under body 12, is in practice, packed with absorbent waste to receive the lubricant with which the journal is supplied as it is dropped from the journal which normally rests on the brass 14.

As best shown by dotted lines in Figure 2 of the drawings, the journal 15 is disposed in service relation to the upper edge of the flanges 11. The space between the flange 11 and the bottom of the journal 15 when the same is in contact with the brass 14, permits the separation of the axle 15 from the seat 14, or a drop in the wheel with which the journal is associated, when by reason of inequalities in the track, the rail at any point is depressed.

It will be seen, however, that when the journal drops to this extent, it rests upon waste which is packed in the pocket formed by the flanges 11, such lubricant having been previously emitted from the bearing formed by the brass 14.

In the present invention lubricant is introduced through a passage formed in the wood bolster upon which the bolster plate 16 is secured, to communicate with the depression or sump 17. The sump 17 has a central opening 18 for directing lubricant delivered thereto, through the passage 19 in the top wall of the chair 20. The chair 20 is also provided with end-openings through which lubricant may be introduced to the chamber 26. When desired, these end-openings may be closed.

As best seen in Figure 2 of the drawings, the chair 20 is provided with the brass 14 which is rigidly secured thereon, and is held by the lip edges 21 of the said chair, so that the lubricating passage 22 in the brass 14 aligns with the lubricating passage 23 in the said chair.

As also shown in Figure 2 of the drawings, the casting 13 forms a rectangular recess 24 for holding the chair 20. The benches 25 formed in the said casting, 110

support the said chair, when the axle or journal 15 thereof is removed or dropped as in service, and in the manner as above indicated. Figure 2 also shows the curved shapes of the side walls and top of the said chair in cross section, which provide for the rolling or rocking of the said chair for self-aligning to the stresses imposed by the load on said chair.

10 In Figures 3, 4, and 5, the outer shape of the chair 20 in the longitudinal extension of the walls thereof, is disclosed as is also the end or thrust walls of the said chair.

15 The curvature of all of the exposed walls of the chair 20 provides for the self-aligning of the chair in correspondence with the stresses on the journal.

20 The chair 20 is hollowed to form the lubricant box 26. The bottom of the box 26 is formed by the arch 27, of the chair 20. This construction provides pockets 28 at the opposite extremities of the arch 27, the said pockets extending lengthwise of the chair. The pockets 28 thus formed, furnish reser-25 voirs for lubricant, which in the service operation of the car, is thrown back and forth from the pocket on one side of the said chair, to the pocket on the other side, across the said crown. As the lubricant is 30 thus thrown from one pocket to the other, a certain proportion thereof is delivered into the passages 22 and 23, and there- through to the journal 15.

35 The inner end of the passage 22 has a flare 29, the inclined walls of said flare serving to prevent the retention of any possible grit or dirt carried thereby, the tendency whereof, is to form a plug or stoppage for the passage 22. In other words, the flare 29 40 serves at all times to clear the delivery opening of the passage 22.

45 When cars are provided with journal boxes constructed as shown in the above drawings, and as above described, the operation of lubricating the journals is as follows:

50 A grease-gun or similar tool is introduced so that the lubricant carried thereby may be deposited in the sump 17, where the chair is provided with the end-openings such as shown in Figure 4 of the drawings. The lubricant may be introduced into the chamber 26 through the said openings. The lubricant is delivered through the passage 55 19 to the chamber 26. The lubricant which is generally used is heavy oil or grease. As much of the lubricant as can be crowded into the chamber 26 is delivered thereinto. When the journal 15 turns under the brass 60 14, sufficient heat is generated to flow the lubricant. The surplus lubricant is delivered through the passages 22 and 23 to the bearing surface of the journal 15 and brass 14. The bulk of the lubricant flows 65 to the pockets 28 and is retained therein,

after the surplus is passed from the chamber 26. The excess of lubricant when carried past the brass 14 is deposited on the waste in the pocket formed by the flanges 11.

70 After the excess of lubricant has been delivered from the chamber 26, a continued lubrication of the bearing is affected by the liquid lubricant held in the pockets 28, being delivered to the passages 22 and 23, as the said lubricant is washed into the said 75 passages in correspondence with the operation of the car or the bearing formed by the box connected therewith.

80 It is obvious that the reservoir of lubricant in the pockets 28 will be available for a considerable time, due to the fact that as the reserve diminishes, the supply drawn therefrom diminishes in a substantially corresponding degree.

85 While the preferred construction is shown in the drawings as one employing the flanges 11 for forming a pocket for waste has been described, it will be understood, that in some bearings the flanges 11 may be dispensed with, and the under body 12 may 90 be correspondingly raised. In this case, the bearing 15 would be limited in its separation from the seat 14, not by the edges of the flanges 11, but by the inner surface of the under body 12. This becomes necessary 95 where it is found expedient to reduce the extension of the bearing casting from the bolster of the car.

Claims.

100 1. In a bearing as characterized, a journal box having its hollow interior formed to provide a lower relatively narrow portion and an upper portion enlarged in opposite directions to either side of the side walls of the lower portion, and a bearing member disposed within the upper enlarged portion of said journal box and comprising a hollow body having an arched bottom wall extending across the upper open end of the lower portion of said journal box and forming lubricant receiving pockets at the opposite sides of the ridge portion thereof, said arched bottom wall having an opening 105 formed in the ridge thereof for the passage through the same of the lubricant in its movement from one pocket to the other, whereby the lubricant passing downwardly of the opening will discharge onto the upper surface of an axle passing through the lower portion of said journal box.

110 2. In a bearing as characterized, a journal box having its hollow interior formed to provide a lower narrow portion and an upper portion enlarged in opposite directions to either side of the side walls of the lower portion, a bearing member disposed within the upper enlarged portion of said journal box and comprising a hollow body having an arched bottom wall extend-115 120 125 130

ing longitudinally of the upper open end of the lower portion of said journal box and forming lubricant receiving pockets at the opposite sides of the ridge portion thereof, 5 said arched bottom wall having an elongated opening formed longitudinally of the ridge thereof for the passage through the same of the lubricant in its movement from one pocket to the other, whereby the lubricant 10 passing downwardly of the opening will discharge onto the upper surface of an axle passing through the lower portion of said journal box, and means for introducing a lubricant to the interior of said bearing 15 body.

3. In a bearing as characterized, a journal box having its hollow interior formed to provide a lower narrow portion and an upper portion enlarged in opposite directions 20 to either side of the side walls of the lower portion, and a bearing member disposed within the upper portion of said journal box and comprising a hollow body having an arched bottom wall extending longitudinally 25 of the upper open end of the lower portion of said journal box and forming lubricant receiving pockets at the opposite sides of the ridge portion thereof, said arched bottom wall having an elongated opening 30 formed longitudinally of the ridge thereof for the passage therethrough of the lubricant in its movement from one pocket to the other, whereby the lubricant passing downwardly of the opening will discharge 35 onto the upper surface of an axle passing through the lower portion of said journal box, said journal box having an opening in the upper side thereof for the introduction of a supply of lubricant therethrough 40 and through a filling opening formed in the upper side of said journal box and aligned therewith for the purpose.

4. In a bearing as characterized, a journal box having its hollow interior formed to 45 provide a lower narrow portion and an upper portion enlarged in opposite directions to either side of the side walls of the lower portion, a bearing member disposed within the upper enlarged portion of said journal 50 box and comprising a hollow body having an arched bottom wall extending longitudinally of the upper open end of the lower portion of said journal box and forming lubricant receiving pockets at the opposite 55 sides of the ridge portion thereof, said arched bottom wall having an elongated opening formed longitudinally of the ridge thereof for the passage therethrough of the lubricant in its movement from one pocket 60 to the other, said hollow body having a filling opening formed in the top wall thereof, and a bolster plate for supporting said journal box in position, said bolster plate having a filling opening formed therein and 65 arranged in registry with the said filling

opening of said hollow body for the introduction therethrough of a lubricant to the interior of said hollow body.

5. In a bearing as characterized, a bolster plate, a journal box carried by said bolster plate, a bearing member housed within the upper portion of said journal box and having a hollow interior, and a bottom wall arched inwardly of said bearing member and forming pockets at the opposite sides of the 70 ridge portion thereof, said arched bottom wall having an elongated opening formed longitudinally of the ridge thereof for the passage therethrough of the lubricant in its movement from one pocket to the other 75 thereof, the top wall of said bearing member having a filling opening therein, said bolster plate having a lubricant receiving opening formed therethrough and arranged in registry with the said filling opening of said 80 bearing member for the introduction of a supply of lubricant therethrough and into the interior of said bearing member.

6. In a bearing as characterized, a bolster plate, a journal box carried by said bolster plate, a hollow lubricant receiving body mounted within said journal box, a bottom wall arched inwardly of said body and forming pockets at the opposite sides of the ridge portion thereof, said arched bottom wall 90 having an elongated opening formed longitudinally of the ridge thereof, and a bearing member carried at the under side of the bottom wall of said hollow body and having an opening therein complementary to the elongated opening thereof, the top wall of said hollow body having a filling opening therein, said bolster plate having a lubricant receiving opening formed therein and arranged in registry with the said filling opening of said hollow body for the introduction therethrough of a lubricant to the interior 95 of said hollow body.

7. In a bearing as characterized, a bolster plate, a journal box carried by said bolster plate, a hollow lubricant receiving body, a bearing member carried by said hollow body, said hollow body and the bearing member carried thereby being loosely mounted within said journal box whereby to be self-adjustable when operative, and a bottom wall arched inwardly of said hollow body and forming pockets at the opposite sides of the ridge portion thereof, said arched wall having an elongated opening formed longitudinally of the ridge portion thereof and in registry with a similarly formed opening in said bearing member carried by the hollow body, the top wall of said hollow body having a filling opening therein, said bolster plate having a lubricant receiving opening formed therein and arranged in registry with the said filling opening of said hollow body for the introduction therethrough of a lubricant to the interior of said hollow body.

8. In a bearing as characterized, a bolster plate, a journal box carried by said bolster plate, a hollow lubricant receiving body, and a bearing member carried by said hollow body, said hollow body being mounted within said journal box and having its opposite side walls reversely curved for rolling contact with the opposed straight side walls thereof whereby to be, together with the bearing member carried by the same, self adjustable when operative, said hollow body having its bottom wall inwardly arched on the longitudinal center thereof to form pockets at the opposite sides of the ridge portion of the wall, said arched wall having an elongated opening formed longitudinally of the ridge portion thereof and in registry with a similarly formed opening in the bearing member carried thereby, the top wall of said hollow body having a filling opening formed therein, said bolster plate having a lubricant receiving opening formed therein and arranged in registry with the said filling opening for the introduction therethrough of a lubricant to the interior of said hollow body.
9. In a bearing as characterized, a journal box, an axle extending into the lower portion of said journal box, a lubricant receiving body mounted within the upper portion of said journal box and having a discharge opening through the bottom wall thereof, and a bearing element for said axle mounted on the under side of said body and having an opening therein disposed in registry with the opening of the body for the discharge therethrough and onto the upper surface of said axle of a supply of the lubricant.
10. In a bearing as characterized, a journal box, an axle extending into the lower portion of said journal box, a lubricant receiving body mounted within the upper portion of said journal box and having a discharge opening in the bottom wall thereof, a bearing element for said axle mounted on the under side of said body and having an opening therein disposed in registry with the opening of said body for the discharge therethrough and onto the upper surface of said axle of a supply of the lubricant, and means formed on said body and cooperative with the opposed walls of said journal box whereby the body and the bearing element carried thereby are rendered self-centering.

JAMES R. FLEMING.
